UNITED STATES PATENT OFFICE.

ROBERT ROBINSON, OF BROOKLYN, NEW YORK.

FAUCET.

SPECIFICATION forming part of Letters Patent No. 274,385, dated March 20, 1883.

Application filed May 5, 1882. (No model.)

To all whom it may concern:

Be it known that I, ROBERT ROBINSON, of Brooklyn, in the county of Kings and State of New York, have invented certain new and useful Improvements in Faucets; and I do hereby declare that the following is a full, clear, and exact description thereof, reference being had to the accompanying drawings, and to the letters of reference marked thereon, which form 10 part of this specification.

My invention relates to improvements in faucets in which equal quantities of two liquids can be drawn from one discharge-pipe or a given quantity of one or both liquids; in 15 other words, in which one education-port can be brought in communication with one or two supply-ports, as desired; and the object of my improvement is to obtain this end with the maximum simplicity of construction. I attain 20 this object by the mechanism illustrated in the accompanying drawings, in which—

Figure 1 represents a sectional elevation of one form of cock embodying my invention. Fig. 2 is an elevation of the plug A, showing 25 the relative location of the induction and education ports, the former in full and the latter in dotted lines. Fig. 3 is a similar elevation, showing the education-ports in full and the induction in dotted lines. Fig. 4 represents another form of faucet embodying the principle 30 of my invention, and Fig. 5 a sectional elevation of the plug, showing the relative location of the supply-ports B B'.

A represents the plug of the faucet, which, 35 as illustrated by Figs. 1, 2, and 3, has a supply-port, B', in the upper hollow part thereof, communicating with pipe E, and an education-port, B'', in the lower hollow part, communicating with pipe G.

In the lower solid part of the plug is a supply-port, B, communicating with the pipe F, its education-port B''' being in a direct line on 40 the opposite side, also facing the common education-pipe G. The supply-ports B B' are cut in such a manner that their inner longitudinal walls are in the same straight line parallel to the axis.

The plug is mounted in a casing, E', having a swivel-bearing therein. Its lower end is 45 threaded, so as to engage a nut, C, holding in place a washer, J. Motion is imparted to the plug by a crank, D, in the form shown in Fig. 1, by the education pipe or bib G, as shown in Fig. 4.

E and F are pipes communicating with separate reservoirs. 55

For practical purposes the plug describes an arc of one hundred and eighty degrees. When the plug is in a normal position—that is, when the crank D or bib G is at zero or 60 one hundred and eighty degrees—the cock or faucet is closed. When the plug is rotated, so that its angle is forty-five degrees, the education-pipe is in communication with the pipe E, and only one kind of liquid is drawn. 65 When the plug is rotated until its angle is ninety degrees the discharge or education pipe G is in communication with both the pipes E and F, and an equal quantity of each liquid is drawn. When the plug is rotated until its angle is one hundred and thirty-five degrees 70 the education-pipe G is in communication with the pipe F, and only one kind of liquid is drawn. When the plug is rotated until its angle is one hundred and eighty degrees the 75 education-pipe G is in communication with neither of the pipes E F, and hence no liquid is drawn.

In the construction shown in Fig. 4 the plug A is held in the casing E' by a threaded nut, 80 C, at the lower end, and at its upper end by a threaded nut, I, engaging with exterior threads on the casing E', forming thereby a binding contact between the plug A and the elastic unthreaded portion of the casing. 85

The education-pipe G is screwed into the threaded head of the plug A, so that its duct shall be in alignment with that of the plug A, as shown in Fig. 4.

Having described my invention, what I claim, and desire to secure by Letters Patent of the United States, is—

1. In a faucet, a plug having supply-apertures cut therein, so that their inner longitudinal walls abut on the same straight line parallel to the axis, substantially as set forth. 90

2. In a faucet, in combination with a casing, E', having supply-pipes E F and discharge-pipe G, a plug, A, partially hollow, having apertures B B' B'' B''', and means for imparting rotation to said plug, substantially as set forth. 95

In testimony that I claim the foregoing as my own I affix my signature in presence of two witnesses.

Witnesses: ROBERT ROBINSON.

F. A. ROBINSON,
W. M. PICKSLAY.
